LAZARUS WHITE, OF NEW YORK, N. Y.

HYDRAULIC PILE DRIVING MECHANISM

Application filed May 1, 1929. Serial No. 359,592.

This invention relates to certain arrangements for hydraulically driving a pile or the like.

In certain pile driving or setting operations, such as the piles that are used for underpinning structures, hydraulic rams are used which are placed on the top of a pile in an erect position, that is, with the piston part of the ram pointing upwardly, this piston exerting its pressure against a suitable abutment, such as a plate or the like, secured beneath the foundation of the building. In the operation of these rams, very heavy pressures are required and the parts, because of such pressures, which frequently are as high as 6000 pounds to the square inch, have to be very strong and heavy, as well as the piping and their connections required for supplying the fluid pressure to the rams.

In certain pile driving operations, the piles are in the form of metal cylinders which, because of limited headroom beneath the foundation, are in short sections, and as each section is driven a new section has to be put in place. This placing of the cylinder sections in position heretofore required the removal of the rams for each section, and the constant removal of the rams and disconnection of the piping is troublesome and consumes time, and is apt to cause leakage either in the rams or in the connections. Furthermore, owing to the limited throw of the rams, blocking had to be inserted between the top of the pile and the ram, and, to permit this, the ram and connections had to be removed each time to insert a block.

It is the especial object of the present invention to provide an arrangement of the ram and its connecting parts so that the ram and connections do not have to be removed from their positions during the entire operation of driving these sectional piles, so that the labor required for driving the pile is greatly reduced and the other disadvantages above referred to are obviated.

It is a further object of the invention to provide a construction of simple character in which the rams may be readily placed in position and operated to permit the placing in position of the cylinder sections.

With these and other objects not specifically referred to in view, the invention consists in certain novel parts, arrangements and combinations which will be described in connection with the accompanying drawings and the novel features pointed out in the claims hereunto appended.

In these drawings—

Figure 1 is a side elevation, partly broken away, of an arrangement embodying the invention;

Figure 2 is an edge view of the construction shown in Figure 1;

Figure 3 is a top view of the construction shown in Figure 1, certain parts being omitted, and

Figure 4 is a detail view, showing the blocking used as the driving of the pile section proceeds.

Generally speaking, the improved arrangement consists in reversing the position of the cylinder and ram so that the piston part of the ram extends downwardly and has a downward movement with the pile it drives, the hydraulic cylinder of the ram being suspended from the abutment against which the pressure of the ram is applied, together with the means for retracting the piston of the ram when it is desired to place a cylinder section in position, and a preferred embodiment of the invention is shown in the drawings.

Referring to these drawings, there is provided a hydraulic cylinder 1 to which fluid under pressure may be supplied through a pipe 2 controlled by a valve 3 from any suitable source of fluid pressure by means of a pipe 4 connected with such source, which is not illustrated. This hydraulic cylinder is suspended from an abutment against which the pressure fluid in the cylinder works, and this cylinder is placed in position in any suitable manner. In the preferred construction, the closed end of the cylinder has secured thereto, as by welding, a plate 5 which slides sideways in guides 6 secured to a plate 7, in turn secured, in any suitable manner, as by bolts 8, to a jacking plate 9 which bears against a part of the structure beneath which the piles are being driven, this being illus-

trated, in the present instance, as an I-beam 10. Secured in the cylinder, so as to have a reciprocating movement therein, is a piston 11 which works downwardly during the driving operation, this piston driving against a plate 12 placed on top of one of the pile sections 13.

After the section 13 has been driven, it is necessary to insert another section above it, 10 and, in accordance with the invention, means are provided for retracting the piston away from the driven section to permit a new section to be placed in position. While these means may vary, a convenient one is that 15 shown in which there is provided a rack 14 secured, as by a bolt 15, to the outside of the piston, and cooperating with this rack is a pinion 16 on a stud 17, the pinion and stud being supported in a split collar 18, and the 20 piston being operated by means of a hand-spoke or bar 19. To prevent the piston from falling out of the cylinder, a stop 20 may be provided at a suitable point on the rack. The piston is or may be made fluid-tight by 25 means of a cup washer 21, indicated by dotted lines in Figure 1.

An important feature of the invention is that the pipe connections for supplying liquid under pressure to the ram may be secured 30 in place for a given job and will be out of the way overhead. This is specially advantageous where such high pressures are being employed, because of the necessity of maintaining tight joints. By the arrangement of 35 the pipe connections overhead, it becomes possible to provide conveniently a centrally located power pump with or without an accumulator, thereby avoiding the use of the ordinary hand operated hydraulic jacks and 40 greatly speeding up the operations.

Owing to the short throw of the ram piston, after the pile has been driven a short distance, blocking, as pipe sections 23, are employed, a second driving plate 24 being placed 45 on top of a section 23 against which the ram works.

With the arrangement above described, the mechanism remains in position until the pile has been driven to its full depth, and does not 50 have to be removed for the insertion of each pile section, the only part requiring removal being the driving plate 12. The pressure behind the piston is reduced by a bleeder valve 22. Thus the apparatus and the connections 55 may be used for driving each pile without more than ordinary strains and stresses. Further, by inverting the parts, the cylinder tends to remain clean and dirt does not work into it, or, if it does, tends to work out, so 60 that scoring of the ram cylinder is obviated.

While the invention has been shown and 65 described in its preferred form, it will be understood that certain variations are permissible in the construction and arrangements 70 of the parts and in the means for retracting

the cylinder without departing from the invention as defined in the appended claims.

What is claimed is:

1. In an arrangement for hydraulically driving a pile or the like, the combination 70 of a fixed abutment, a hydraulic cylinder removably secured to and beneath the abutment whereby the abutment absorbs the thrust therefrom, a piston arranged to drive in a downwardly moving direction in the cylinder, and means for retracting the piston away from the top of a pile.

2. In an arrangement for hydraulically driving a pile or the like, the combination of 75 a fixed abutment, a hydraulic cylinder removably secured to and beneath the abutment whereby the abutment absorbs the thrust therefrom, a piston arranged to drive in a downwardly moving direction in the cylinder, and a rack and pinion for retract- 80 ing the piston away from the top of a pile.

3. In an arrangement for hydraulically driving a pile or the like, the combination of 85 a fixed abutment, guides in the abutment, a hydraulic cylinder slidable into position in the guides, a piston in the cylinder arranged to drive in a downwardly moving direction, and means for retracting the piston away from the top of a pile.

4. In an arrangement for hydraulically 90 driving a pile or the like, the combination of a fixed abutment plate, guides in the abutment, a hydraulic cylinder slidable into position sidewise in the guides, a piston in the cylinder arranged to drive in a downwardly 100 moving direction, and a rack and pinion for retracting the piston away from the top of a pile.

5. In an arrangement for hydraulically 105 driving a pile or the like, the combination of a fixed abutment, a hydraulic cylinder removably suspended from the abutment whereby the abutment absorbs the thrust therefrom, a piston in the cylinder arranged to drive in a downwardly moving direction, 110 means for retracting the piston away from the top of a pile, and means for preventing the piston from dropping out of the cylinder.

6. In an arrangement for hydraulically 115 driving a pile or the like, the combination of a fixed abutment, a hydraulic cylinder removably suspended from the underside of the abutment whereby the abutment absorbs the thrust therefrom, a piston in the cylinder arranged to drive in a downwardly moving 120 direction, means for retracting the piston away from the top of the pile, and means for preventing the piston from dropping out of the cylinder.

In testimony whereof, I have hereunto set 125 my hand.

LAZARUS WHITE.
